(57) **CLAIM**

The ornamental design of a water ride, as shown and described.

DESCRIPTION

FIG. 1 is a perspective view of a water ride showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The design consists of the features of shape, configuration and ornament of the portions of a water ride shown in solid lines in the drawings. The portions shown in stippled lines do not form part of the design. The lines consisting of short and long dashes in FIGS. 1 to 7 do not form part of the design and are included solely for the purpose of illustrating the boundary of the design.
